Primary Examiner — Elizabeth A. Albert(74) *Attorney, Agent, or Firm* — John Maldjian; Maldjian Law Group LLC(57) **CLAIM**

The ornamental design for a bouquet holder, as shown and described.

DESCRIPTION

FIG. 1 is a perspective view of a bouquet holder showing our new design;

FIG. 2 is a front plan view thereof;

FIG. 3 is a rear plan view thereof;

FIG. 4 is a left plan view thereof;

FIG. 5 is a right plan view thereof;

FIG. 6 is a top plan view thereof; and,

FIG. 7 is a bottom plan view thereof.

The broken lines in the drawings are included to show features that form no part of the claimed design.

1 Claim, 7 Drawing Sheets(56)
